UNITED STATES PATENT OFFICE

ROSWELL F. HATCH, OF WEST HARTFORD, CONNECTICUT, ASSIGNOR TO HARTFORD-EMPIRE COMPANY, OF HARTFORD, CONNECTICUT, A CORPORATION OF DELAWARE

GLASS-FABRICATING MACHINE

Application filed October 28, 1927. Serial No. 229,461.

My present invention relates to glass fabricating mechanism wherein a parison is first formed in a parison-mold and is then transferred to and blown to finished form in a blow-mold. 5

In some types of these machines, particularly in the non-turret type, the blow-mold is moved into the transfer position and then moved away therefrom, as for instance to 10 make way for another blow-mold which receives a parison from the same source. In such machines the parisons are blown to final form while the blow-molds are still in the transfer position. As the time required to 15 blow the parisons to final form in the case of some characters of ware is relatively long, the result is that if such ware be fabricated on these types of machines the cycle of parison formation and transfer is prolonged and the 20 rate of production materially reduced.

The object which I have in view is the improvement of such machines to enable them to produce such ware without slowing up their operation or reducing their production 25 rate and at the same time providing sufficient time for the finishing blows.

In accordance with my invention I provide means whereby the application of the finishing blow to the parison which has been 30 deposited in the blow-mold may proceed while the blow-mold is moving away from the transfer position so that another blow-mold may without delay be moved into the transfer position to receive the next parison.

35 Preferably I arrange the finishing blow to start before the blow-mold is moved from the transfer position and to continue the finishing blow through as much of said movement as is necessary to provide the requisite blowing 40 period. However, if necessary, the application of the finishing blow may be continued until after the blow-mold has attained its other or take-out position.

45 Novel features of construction and also of arrangement of parts will appear from the following description:

In the accompanying drawings wherein I have illustrated the best embodiment of the principles of my invention now known to me, 50 Fig. 1 is a plan view; Fig. 2 a rear eleva-

tion, and Fig. 3 partially an end view looking from the right in Fig. 1 and partially a sectional view through the parison-mold mounting and the transfer device.

Referring to the drawings, a parison-mold is indicated at 1 and two blow-molds at 2 and 3 respectively. The parison-mold is mounted on a hollow base 4 and the blow-molds are mounted in spaced relation on the box support 5 which in turn is slidably 55 mounted on a base 6 which is rigid with the base 4. The path of the movement of the box 60 5 is transverse to the long axis of the base 4.

The molds are of the portable type and as the mechanisms for opening and closing the 65 several molds are alike and are not in themselves the subject matter of the present invention I will briefly describe that of the parison-mold only.

The mold-parts are carried respectively by 70 the concentric sleeves 7 and 8 which are rotatably mounted on the vertical pintle 9. Said sleeves are coupled by crank and link connections to the pinions 10 and 11 respectively, and said pinions are rotated to open and 75 close the mold by a double rack 12 carried by the piston rod 13 of a fluid pressure cylinder 14.

15 indicates the portable neck-ring which, 80 when the parison-mold 1 is closed, is positioned below the same. The neck-ring parts are carried by the levers 16 which are mounted on the brackets 17 mounted on a shaft 18 for limiting longitudinal movement 85 for opening and closing the neck ring parts. The ends of the shaft 18 are journaled in the stands 19 rising from the base 4. Between the brackets said shaft is provided with a pinion 20 meshing with a vertically disposed rack 21 on the piston rod 22 of the fluid pressure cylinder 23. The neck-ring thus forms 90 a part of the transfer device by means of which the parison, when the parison-mold is opened, is swung up out of the parison-mold and is deposited in the blow-mold which is in 95 the transfer position occupied by the blow-mold 2 in the drawings.

24 is the neck-forming plunger carried by 100 the piston rod 25 of the fluid-pressure cylinder 26 and employed to enter the neck-ring

from below to assist in forming the neck of the parison.

27 is a blow-head, which is swung into capping relation with the parison-mold 1 after the mold-charge has been deposited in the latter to compact the mold-charge down into the neck-ring and the parison-mold.

The box 5 is periodically moved back and forward to alternately spot the blow-molds 10 2 and 3 in the transfer position to receive a parison, such position being shown in the case of the blow-mold 2 in the drawings. Thus 28 is a fluid-pressure cylinder supported from the base 4 and having its piston rod 29 15 connected to the box 5.

Each of the blow-molds has associated with it a blow head 30 which is arranged to be moved over into alignment with the upper end of the blow-mold and then lowered into 20 capped relation with the latter and after the completion of the blowing operation to be raised from the blow-mold and to be swung aside out of the way.

Thus I have shown the blow head mounted on the outer end of an arm 31 clamped on the upper end of the extension 32 of the piston rod of a fluid-pressure cylinder 33 which is mounted on the box 5. The extension 32 is arranged for rotary movement on 30 its axis, and such movement is provided for by the slot 34 in the fixed sleeve 35 through which said extension 32 extends, said slot being engaged by a pin 36 on said extension. The slot 34 is laid out to provide the swinging movement of the blow-head hereinbefore mentioned.

In the operation of the machine, the blow-molds are, by the movement of the box 5 alternately brought into the transfer position, and when the parison has been deposited in the blow-mold the blow-head associated with the blow-mold is positioned in capped relation with the mold and the blowing operation begun and proceeded with while the blow-mold is being moved away from the transfer position and another blow-mold moved into said position, and if desired until the take-out is about to occur.

It is thus evident that a blowing period 50 sufficient to finish substantially all kinds of parisons may thus be provided for in connection with the types of machines herein referred to.

Obviously my improvement enables the 55 rate of production of the machine to be greatly increased owing to the elimination of the lag or delay which now takes place while the parison is being finished in the blow-mold remaining in the transfer position, and 60 the machines are also adapted for the fabrication of ware which hitherto could not be fabricated thereby owing to the brief periods during which the finishing blow could be applied.

65 What I desire to claim is:—

1. In a glass fabricating machine, the combination of a fixed parison-mold, a slidably mounted blow-mold, means for transferring the parison from the parison-mold to the blow-mold, means for periodically moving the blow-mold into and away from the transfer position, and blowing means moving with the blow-mold for blowing the parison in the blow-mold while the latter is moving away from its transfer position. 70

2. In a glass fabricating machine, the combination with a parison-mold located in a fixed neck-down position, of a plurality of blow-molds each mounted in a neck-up position and each having a cycle of operation 80 including movement relative to the parison-mold and into and away from a transfer position, means for transferring the parisons from the parison-mold to the blow-molds and simultaneously inverting said parisons, and 85 individual blowing means for each blow-mold said blowing means being arranged for blowing during any selected portion of the cycle of operation of the corresponding blow-mold. 90

3. In a glass fabricating machine, the combination with a parison-mold located in a fixed position, of a pair of blow-molds, means for reciprocating said blow-molds so as to position them alternately in transfer relation with the parison-mold, means for transferring parisons from the parison-mold alternately to each blow-mold when it is in the transfer position, and individual blowing means for each mold and movable therewith. 95

4. In a glass fabricating machine, the combination with a parison-mold located in a fixed neck-down position, of a plurality of blow-molds disposed in neck-up position, a slide upon which said blow-molds are mounted, means or reciprocating said slide to present said blow-molds successively to a transferring position, means for successively transferring parisons formed in said parison-mold from a neck-down position in said parison-mold to a neck-up position in the blow-mold in said transfer position, and means moving with each of said blow-molds for supplying final blowing air to the parison within said blow-mold. 105

Signed at Hartford, Conn., this 27th day of October, 1927.

ROSWELL F. HATCH.
